United States Patent Office

Des. 228,145
Patented Aug. 14, 1973

228,145

CANDELABRA

Robert L. Gordon, 3957 Drake's Branch Road,
Nashville, Tenn. 37218

Filed Apr. 10, 1972, Ser. No. 242,910

Term of patent 3½ years

Int. Cl. D26—01

U.S. Cl. D48—2

Fig. 2

Fig. 3

FIG. 1 is a side elevational view of a candelabra, showing my new design;

FIG. 2 is a top plan view thereof, the base being omitted for convenience of illustration; and

FIG. 3 is a bottom plan view thereof, disclosing only the bottom layer of candle holders for convenience of illustration.

I claim:

The ornamental design for a candelabra, as shown and described.
